UNITED STATES PATENT OFFICE.

JAMES THORNTON, OF LONG BRANCH, NEW JERSEY.

BLIND OR SHUTTER FOR WINDOWS.

SPECIFICATION forming part of Letters Patent No. 340,387, dated April 20, 1886.

Application filed November 20, 1885. Serial No. 183,457. (No model.)

To all whom it may concern:

Be it known that I, JAMES THORNTON, a citizen of the United States, residing at Long Branch, in the county of Monmouth and State 5 of New Jersey, have invented a new and useful Blind or Shutter for Windows, &c., of which the following is a specification.

My invention relates to transom blinds or shutters and means for operating the same, and 10 also to the construction of the top of the window to adapt it to receive the transom blind or shutter.

The object of the invention is to furnish means for lighting and ventilating apartments 15 without exposing the interior and without causing drafts.

In the accompanying drawings, Figure 1 represents a front elevation of a window provided with my improved transom-blind. Fig. 20 2 is a vertical section of the window, taken on line *xx* of Fig. 1.

Referring to the drawings, A represents a window-frame; B, the sash, and D D the ordinary swinging blinds or shutters, hung in the 25 usual manner. Over the top of the window-frame a hood or cornice, E, is constructed, and supported by ornamental brackets *aa* or other suitable means.

F represents the transom blind or shutter. 30 It is placed in the window-frame outside the sash rabbets or grooves, and is hung by suitable hinges to the window-frame above or over the blinds D.

As shown, the transom blind or shutter is 35 hung by its upper edge and opens upward; but I do not limit myself to that manner of hanging it. The lower or free edge of the transom-blind is provided with a rabbet, b, which, when the blind is closed, matches with 40 a corresponding rabbet, b', on the tops of the blinds D D, forming thereby a flush connection. The transom-blind, by this construction, also serves as a lock or fastening for the tops of blinds D D.

45 The opening, closing, and adjusting of the transom-blind are done from the interior, and by devices which will now be described. Under the hood and near the front thereof is pivoted a pulley, d. Through the 50 window-frame, in line with the pulley, is made

an opening, e, communicating with the interior, and at or about the inner end of said opening is pivoted another pulley, d'.

A chain, G, having one end attached to the outside of the free or swinging edge of the 55 transom blind or shutter, is passed up over pulley d, thence horizontally through opening e, over pulley d', and its free end g hangs down alongside the window-facing in the apartment. 60

A hook, f, or other suitable device may be attached to the window-facing, or at some other convenient point, to fasten the chain to.

By means of the chain the transom-blind 65 can be operated from the interior and opened and closed.

More than one chain may be used, if deemed necessary, and the mode of attaching the chain to the blind may be modified or changed to adapt it to any change in the 70 hanging of the blind that may be adopted. Moreover, in place of the chain and pulley, any other mechanical device capable of being utilized for opening and closing and adjusting the transom-blind may be substituted 75 for it.

By means of the transom blind or shutter light can be admitted to the apartment without exposing the interior thereof. Air also can be admitted without creating a draft. Thus, 80 when the lower part of the window is necessarily closed from any cause, the upper part can be opened and light and air admitted through the transom-opening, thus giving ample light to the apartment, producing perfect ventilation, and at the same time the inmates or occupants of the apartment are protected against exposure. The projecting hood or cap shields the transom-opening, preventing the rain from beating in over the 85 transom, and also shading it from the sun's rays. 90

I claim—

1. In combination with the window frame, sash, or blinds, a transom blind or shutter 95 hung above or over the blinds D D, and connected with the interior of the apartment by a chain, so that it can be operated and adjusted from the interior without opening the window, substantially as specified.

2. The combination of the window-frame provided with the opening *e*, the sash, the transom-blind, the chain, and the pulleys, substantially as specified.
- 5 3. The combination of the hood *E* with the transom-blind, connected with the window in the manner described, substantially as specified.
4. The combination of the hood *E*, transom-blind *F*, pulleys *d d'*, chain *G*, and window-frame provided with opening *e*, substantially as specified.

JAMES THORNTON.
